DESIGN FOR AN AIR CONDITIONING MA- CHINE CASING

Guy Paschal, New York, N. Y.

Application September 28, 1936, Serial No. 65,038

Term of patent 3½ years

To all whom it may concern:

Be it known that I, Guy Paschal, a citizen of the United States, residing at 108 East 82nd Street, New York, in the county of New York and State of New York, have invented a new, original, and ornamental Design for Air Conditioning Machine Casings, of which the following is a specification, reference being had to the accompanying drawing, forming a part thereof, in which:

Figure 1 is a plan view of an air conditioning machine casing, showing my new design;

Figure 2 is a front elevational view of Figure 1;

Figure 3 is an end elevational view of Figure 1

as seen from the left side thereof; and

Figure 4 is a side elevational view of Figure 1

as seen from the right side thereof.

I claim:

The ornamental design for an air conditioning machine casing, as shown.

GUY PASCHAL.
